E. G. ERICKSON

OAR LOCK

Filed March 9, 1926

Inventor
E. G. Erickson,

By Clarence A. O'Brien
Attorney

UNITED STATES PATENT OFFICE.

ERICK G. ERICKSON, OF ALEXANDRIA, MINNESOTA.

OARLOCK.

Application filed March 9, 1926. Serial No. 93,478.

This invention relates to oar locks, and has for its primary object to provide means whereby the lock will be retained against accidental displacement within the boat attached receiving keeper for preventing the accidental disengagement of the same therefrom during the manipulation of the oars in the locks.

A further object of the invention is to provide such a locking means that is entirely automatic in its nature and that will permit of the ready insertion of the lock within the keeper, but that is operable to prevent the accidental withdrawal of the lock from the keeper after the same has been arranged therein.

Other objects will become apparent as the nature of the invention is better understood, the same comprising the novel form, combination, and arrangement of parts hereinafter more fully described, shown in the accompanying drawing and claimed.

In the drawing wherein like reference characters indicate corresponding parts throughout the several views;

Figure 1 is a view partly in elevation and partly in cross section of a conventional form of oar lock, and keeper, the lock pin being equipped with my improved retaining means.

Figure 2 is an edge elevation of the lock per se, and

Figure 3 is a perspective of the retaining member per se.

Now having particular reference to the drawing, 5 indicates the conventional form of oar lock keeper that is adapted to be rigidly secured to the gunwale of a boat, the same comprising a plate 6 formed centrally with an oar lock pin receiving sleeve 7. Said sleeve 7 is adapted to receive the conventional pin 8 of an oar lock 9 which in the present instance is formed at its lower end with a cross slot or bifurcations 10. Loosely arranged in said slot 10 is a metallic plate 11, the lower end of which is pointed as clearly shown in Figures 1 and 3, and which pointed end projects beyond the lower slotted end of the lock pin as shown in Figures 1 and 2.

Said plate 11 is formed at its upper end with a pair of vertically spaced parallel and diagonally extending slots 12—12 through

which extend retaining pins 13, extending 55 across the slot 10 in the oar lock pin 8. The formation of the slots 12 are such that the lower ends thereof are directly between the edges of the plate in order that when said plate is forced inwardly of the slot by the 60 action of the pin 8 being inserted into the keeper sleeve 7, the same will be entirely within said slot and also in order that said plate will drop by gravity to the position 65 shown in Figure 1, that is outwardly of the slot 10 at one side thereof for engaging the lower end of the pin sleeve 7 in preventing the accidental displacement of the lock with respect to said keeper. Obviously, when it 70 is desired to withdraw the oar lock, the plate 75 may be moved inwardly of the slot 10 as shown by the dotted lines in Figure 1 so that the edges thereof will register with the edges of the slots to facilitate the passage of the pin through said sleeve.

It will thus be seen that I have provided a highly novel, simple but yet efficient means whereby oar locks may be retained within their keepers but yet permitting of the withdrawal of the same when desired.

Having thus described the invention, what I claim as new and desire to secure by Letters Patent is:—

1. In combination with an oar lock and its keeper, wherein the pin of the oar lock is 85 formed at its lower end with a cross slot, a plate arranged in said slot, said plate being of substantially the same width as the slot but being of greater length than the slot, the lower end of said plate being pointed, 90 said plate provided with a pair of vertically spaced diagonally extending slots, the lower end of the slots being arranged at a point intermediate the sides of the plate, pins extending transversely through the slotted end of the oar lock pin and through the respective slots in the plate, said pins and the cooperating diagonally extending slots permitting the plate to move by gravity whereby one side portion thereof will project beyond the adjacent side of the oar lock pin the projecting portion of the plate adapted to cooperate with the lower end of the keeper to prevent the withdrawal of the oar lock.

2. In combination with an oar lock and its keeper, wherein the pin of the lock is bifurcated at its lower end, a plate provided with vertically spaced diagonally extending slots

arranged in said bifurcation and being of substantially the same width as the bifurcations, pins extending transversely through the bifurcated end of the oar lock pin and through the respective slots, whereby the plates will by gravity project beyond one side of the oar lock pin when the oar lock

is positioned in its keeper, the projecting portion of the plate adapted to cooperate with the lower end of the keeper to prevent 10 the withdrawal of the oar lock.

In testimony whereof I affix my signature.

ERICK G. ERICKSON.
